UNITED STATES PATENT OFFICE.

EMIL HENRIK WIDEGREN AND KLAS AUGUST WIDEGREN, OF ALBY, SWEDEN.

METHOD OF AND MEANS FOR REDUCING LINE CAPACITY.

1,154,278.

Specification of Letters Patent. Patented Sept. 21, 1915.

Application filed December 20, 1913. Serial No. 807,916.

To all whom it may concern:

Be it known that we, EMIL HENRIK WIDEGREN and KLAS AUGUST WIDEGREN, subjects of the King of Sweden, and both 5 residents of Alby, Sweden, have invented new and useful Improvements in Methods of and Means for Reducing Line Capacity, of which the following is a specification.

This invention relates to a method of and 10 means for reducing the influence of the line capacity in actuating electric apparatus at a distance by means of pulsations obtained from a source of continuous electric current. If unidirectional pulsating currents are 15 transmitted from a source of continuous electric current through a connecting line in order to influence intermittently an electric apparatus of a receiving station, for instance a relay, it happens that if the conducting capacity of the line is great, the current pulsations flow together so as to act 20 continuously upon the receiving apparatus. Various methods have been used in order to counteract this disturbing influence of the 25 capacity; the present invention has for its object to provide a new method for this purpose, as well as means necessary for carrying the method into practice. The new 30 method consists, chiefly, in transmitting on the line partly positive and negative pulsations of requisite strength to act upon the receiving apparatus, partly, between said pulsations other pulsations of the same polarity as the following active pulsation, 35 which latter pulsations are so suited as to their strength, that they are not capable to act upon the receiving apparatus, being on the other hand capable to assist effectively in the discharging and recharging of the 40 line before the next following active pulsation is transmitted.

The invention is illustrated in the accompanying drawings.

Figure 1 shows diagrammatically the 45 pulsation curve used according to this invention. Figs. 2 and 3 show diagrammatically some transmitting arrangements for effecting the pulsations illustrated in Fig. 1. Fig. 4 shows the application of the invention to a writing telegraph according to our 50 U. S. Patent No. 1,054,811. Fig. 5 shows a modification of the transmitting apparatus shown in Fig. 4.

The pulsations transmitted through the 55 connecting line according to this invention are on the one hand such as are intended to

influence the receiving apparatus, and on the other hand such as have not to influence the same. The former are in the description herebelow called "active," the latter "passive" ones. The pulsations of both kinds are, besides, of alternating polarity. The order of the various pulsations appears from the curve in Fig. 1. The zero-line is indicated by 1, 2 and the limit of efficiency of the receiving apparatus, *i. e.* the minimum strength of current by which the receiving apparatus becomes operative, is indicated by 3, 4 on the positive side and by 5, 6 on the negative side of the zero-line. In Fig. 1 60 the following pulsations are shown, counted from the left. At 7 there begins at the positive side of the 0-line a passing pulsation. This lasts between the points 8 and 9 and turns at 9 into an active pulsation 9, 10, 11, 12. At 12 this turns into a passive pulsation 65 on the negative side of the 0-line. This passive pulsation lasts between the points 13 and 14 and turns at 14 into the active pulsation 14, 15, 16, 17. The other passive pulsations are 17, 18, 19 and 22, 23, 24 and the active ones 19, 20, 21, 22 and 24, 25, 26, 27. Thus there always follows on an active pulsation a passive one of the opposite sign and 70 on a passive an active one of the same sign. 75 The pulsation-curve therefore may be compared with an alternate current curve, this circumstance very likely being the explanation of the very effective reduction of the influence of the capacity on the active pulsations transmitted, that is effected by such a 80 form of the pulsation curve. Direct experiments have proved that this reduction is very considerable. The arrangements necessary to effect the said pulsation-curve in the connecting line are obviously dependent on the kind of apparatus, to which the method is applied. In Fig. 2 is shown a step-by-step 85 or continuously rotating cylinder or disk 28 (in Fig. 2 developed in a plane), by means of which the said pulsations can be effected. 90 The cylinder or disk 28 is provided with conducting bars insulated from each other and of a number of at least four or a multiple thereof. The bars are in Fig. 2 four, 95 being indicated by 29, 30, 31, 32. On the axle of the cylinder or disk are provided slip rings 33, 34, 35, 36, being insulated from each other and having sliding contacts 37, 38, 39, 40, bearing thereagainst and being 100 connected with the continuous current source 41, the central point of which is connected 105

to earth by an earth connection 42. The sliding contacts 37 and 38 are connected to the positive side of the current source 41 and the former on a higher potential than the latter, while the sliding contacts 39 and 40 are connected to the negative side and the latter on a higher negative potential than the former. Against the disk or cylinder 28 bears a brush 43 connected to the connecting line 44, in which is inserted a receiving apparatus represented by a relay 45. The bars 29, 30, 31, 32 are each connected with one of the slip rings 33, 34, 35, 36 in such a way as to give the pulsations transmitted through the connecting line in the rotation of the disk or cylinder the order indicated in Fig. 1. If, for instance, the disk or cylinder rotates in the direction of the arrow and the bar 29 is connected with the slip ring 34, the bar 30 should be connected with the slip ring 33, the bar 31 with the slip ring 35 and the bar 32 with the slip ring 36. If the bars are more than four, then every fourth bar must give the same kind of pulsation, and therefore these bars should be connected either one with the other or all with one and the same slip ring.

The arrangement shown in Fig. 2 operates in the following manner: When the brush 43 is passed by the bar 29, the connecting line 44 by the slip ring 34 and the brush 38 will be connected to the current source 41 on the positive side thereof and at the lower potential. Thereby a positive passive pulsation is transmitted through the connecting line. The tension is so suited with respect to the limit of action of the receiving apparatus 45, that the latter does not come into operation. When the brush 43 is passed by the bar 30, the connecting line 44 by the slip ring 33 and the brush 37 will be connected to the current source 41 on the positive side and on the higher tension. Thereby a positive active pulsation is transmitted through the connecting line and the receiving apparatus 45 comes into operation. In a similar way, when the brush 43 is passed by the bar 31, there is transmitted a negative passive pulsation, and when it is passed by the bar 32, a negative active one. Thus the pulsation curve will be that shown in Fig. 1. The transmitting apparatus may also be arranged in a somewhat different way. Instead of producing the passive pulsations by connecting corresponding bars 29, 31 to a lower potential at the current source 41, the same effect can be obtained by connecting these bars to the bars 30, 32 of the active pulsations, if only a resistance is inserted between them, as is shown in Fig. 3. The bars 30 and 32 are, as in Fig. 2, each connected with a slip ring 33 and 34 and through these by means of the sliding contacts 37 and 38 to one side of the current source 41. The bar 29 is connected with the bar 30 through

the resistance 46 and the bar 31 with the bar 32 through the resistance 47.

When the sliding contact 43 is passed by the bar 29, a pulsation is transmitted through the connecting line 44, coming from the positive side of the current source 41, sliding contact 37, slip ring 33, bar 30 and resistance 46. The resistance 46 is so proportioned as to render the pulsation passive. When the sliding contact is passed by the bar 31, the current flows from the negative side of the current source 41 through sliding contact 38, slip ring 34, bar 32 and the resistance 47, this resistance being so proportioned as to make the pulsation passive and of the same strength of current as the other passive pulsation. The active pulsations are formed in the same way as described with reference to Fig. 2.

The arrangements shown in Figs. 2 and 3 can for instance be used in Morse telegraph in order to reduce the influence of the line-capacity. In such case one causes the cylinder 28 to move step-by-step for instance under control of a Morse key or a slip previously punched according to the Morse-writing, so that the passive pulsations are transmitted during the intervals between the separate dashes and points in the Morse writing, while the active pulsations are transmitted with longer or shorter permanence for the formation of the points and dashes of the writing.

In Fig. 4 is shown an application of the invention to a handwriting-telegraph system according to our U. S. Patent No. 1,054,811. A is the transmitting and B the receiving station. The cylinder 48 at the transmitting station is shown developed in a plane. It is provided with bars 49, 50, 51, 52, insulated from each other, and against the same bear two brushes 53, 54 movable in the direction of the axis and situated diametrically opposite each other. These brushes are by a suitable transmission connected with the recording pen of a writing apparatus not illustrated, f. i. as shown in our said U. S. Patent No. 1,054,811. On the axle 55 of the cylinder are provided slip rings 56, 57, which are also supposed to be developed in a plane, and against the same brushes 58, 59, 60, 61 are bearing. The slip rings 56, 57, are divided into two bars each of them grasping one half of the periphery. At the slip ring 56 the bar 62 (being in the development in a plane divided in two halves) is through the line 63 connected with the bars 50 and 52 of the cylinder 48. The bar 64 is insulated and not connected with any other bar. At the slip ring 57 the bar 65 (being in the development into a plane divided in two halves) is through the line 66 connected with the bars 49, 51 of the cylinder 48. The bar 67 is only an insulated intermediate piece not

being connected to any circuit. The brushes 58, 59 on the slip ring 56 are connected with the current source 41, the former on the negative side thereof by the line 68 and the latter on the positive side by the line 69. The brushes 60, 61 on the slip ring 57 are also connected with the current source 51 but on a lower potential than the brushes 58, 59 by the lines 70 and 71 respectively. 5 By the line 42 the middle of the current source is connected to earth.

The brushes 53, 54 on the cylinder 48 are each connected with the connecting lines 72, 73 respectively, which are in connection with the receiving station B. There the one line 72 passes through the magnet coil 74 and then to earth, while the other line 73 passes to the magnet coil 75 and then to earth. The electromagnets 74, 75 15 act on the diaphragm armatures 76, 77, thereby controlling the writing device 78 of the receiving station, as described in our U. S. Patent No. 1,054,811.

The operation of the arrangement is as 25 follows: The cylinder 48 rotates in the direction indicated by the arrow. In the position shown, the brush 53 has just been passed by the bar 52 and has come into contact with the bar 49. This bar 49 is by 30 the line 66 in connection with the bar 65 of the slip ring 57, this bar in its turn being through the brush 61 and the line 71 in connection with the positive side of the current source 41 at the lower potential. When 35 the brush 53 is passed by the bar 49, a passive positive pulsation is therefore transmitted to the connecting line 72. This pulsation has no influence on the diaphragm armature 76.

40 When the cylinder 48 has advanced so far in its rotation that the brush 53 has entered on the bar 50, the brush 58 on the slip ring 56 has entered on the bar 64 and the brush 59 on the bar 62. The bar 50 is by the line 45 63 in connection with the bar 62 on the slip ring 56, this bar in its turn being by the brush 59 and the line 69 in connection with the positive side of the current source 41 at the higher potential. The whole time when 50 the bar 50 passes the brush 53, the brush 59 remains in contact with the bar 62, and thus an active positive pulsation is during this time transmitted to the connecting line 72.

55 When the cylinder 48 has turned half a revolution, the brush 53 is placed in the same position as is shown in Fig. 4 for the brush 54, *i. e.* the position in which it is going over to the bar 51. At the same time 60 the brush 60 at the slip ring 57 has come into the same position as is shown in the Fig. 4 for the brush 61, thus being by its line 70 in connection with the negative side of the current source at the lower potential. The brush 61 has now in relation to

the slip ring 57 come into the previous position of the brush 60, thus bearing against the insulated bar 67. The whole time when the brush 53 is in contact with the bar 51, the brush 60 is in contact with the bar 65, 73 and as the bar 51 is by the line 66 in connection with the bar 65, a passive negative pulsation is thereby transmitted to the connecting line 72.

When the brush 53 at last has entered 75 on the bar 52, the brush 58 has been passed by the bar 64 and is bearing on the bar 62, where it stays the whole time while the brush 53 is passed by the bar 52. This bar 52 is through the line 63 in connection with 80 the bar 62 and the latter through the brush 58 in connection with the negative side of the current source 41 at the higher potential. Through the brush 53 there is accordingly in this case transmitted an active negative pulsation to the connecting line 72. 85

During the revolution of the cylinder 48, which has now been followed, a series of pulsations thus has been transmitted through the connecting line 72, giving together a pulsation curve of the form shown in Fig. 1. If the pulsations transmitted through the brush 54 to the connecting line 73 are examined in the same way, it will be found that the form of the pulsation curve 95 in this case will be the same. At the same time as a passive positive pulsation begins to be transmitted through the brush 53, a very similar pulsation begins to be transmitted through the brush 54. The point of time when this passive pulsation turns into an active one is dependent on the position of the brush in the axial direction, so that this turning as a rule is different for the two brushes. They reach, on the other 105 hand, simultaneously the end of the bar that gives this active pulsation and thus turn simultaneously into the following passive negative pulsation. Consequently, as the cylinder 48 here is arranged, there is 110 always a current of the same polarity running simultaneously through the two connecting lines 72, 73. However, there is nothing preventing one from arranging the cylinder 48 in such a manner, that there 115 always is current of opposite polarity in the two connecting lines 72, 73, the two receiving relays 74, 76 and 75, 77 working independently of each other. The connection of the cylinder may in such a case be 120 arranged for instance as is shown in Fig. 3. The figures 48—55 in Fig. 5 indicate the same parts as in Fig. 4. On the axle 55 are placed four slip rings 79, 80, 81, 82. The bar 49 is by line 83, slip ring 79, brush 125 61 and line 71 connected with the current source 41 on the positive side of the earth connection 42, and on the lower potential. In the same manner the bar 50 is by line 84, slip ring 80, brush 60 and line 69 connected 130

with the higher positive potential at the current source 41. The bar 51 is by line 85, ring 81, brush 59 and line 70 connected with the lower negative potential at the current source 41, and the bar 52 is by the line 86, ring 82, brush 58 and the line 68 connected with the higher negative potential.

When the cylinder rotates in the direction indicated by the arrow, there will thus be transmitted through the brush 53 and the line 72, supposing the position shown in Fig. 5, a passive positive pulsation, then an active positive one, then a negative passive one and then an active negative one, etc., which together form a coherent pulsation curve of the form shown in Fig. 1. Through the brush 54 there is transmitted simultaneously to the line 73 a similar series of pulsations, but at the same time as the brush 53 starts with a positive passive pulsation, the brush 54 starts with a negative passive pulsation. Thus there always flows a current of opposite polarity through the two connecting lines.

By using pulsations of the kind above described the result is that the active pulsations which cause the relays 74, 76 and 75, 77 to be operative, in a very small degree are influenced by an eventual capacity in the lines 72, 73, so that the relays will work in exact harmony with the period of time of the separate pulsations determined by the positions of the brushes 53, 54 on the cylinder 48, which is necessary in order to have the recording pen of the receiving apparatus strictly to follow the movements of the pen of the transmitting apparatus.

Having now described our invention, what we claim as new and desire to secure by Letters Patent is:

1. Method of reducing the influence of the line capacity in actuating electric apparatus at a distance by means of pulsations obtained from a source of continuous electric current, consisting in transmitting through an electric line positive and negative pulsations of a strength required for influencing a receiving apparatus, transmitting through said line, between said pulsations, other pulsations of the same polarity as the following pulsation capable of influencing the receiving apparatus, and so suitting the said intermediate pulsations as to their strength that they are not capable of influencing the receiving apparatus but on the other hand capable of partaking in the discharging and recharging of the line before the next following pulsation capable of influencing the receiving apparatus is transmitted, substantially as and for the purpose set forth.

2. A system of transmitting intelligence including a transmitting station connected electrically through a line with a receiving

station, a receiving apparatus at the latter station, a source of continuous current at the transmitting station, a rotating commutator at the same station, means for transmitting alternately through the commutator positive and negative pulsations capable of influencing the receiving apparatus, and means for transmitting through the commutator between said pulsations other positive and negative pulsations not capable of influencing the receiving apparatus.

3. A system of transmitting intelligence including a transmitting station connected electrically with a receiving station, a receiving apparatus at the latter station, a source of continuous current at the transmitting station, a rotating commutator at the same station, means for connecting some of the bars of said commutator alternately with the negative and the positive terminals of the current source, and means for connecting other bars of the commutator alternately with points of the current source having lower potential than said terminals.

4. A system of transmitting intelligence including a transmitting station connected electrically through lines with a receiving station, a receiving apparatus at the latter station, a source of continuous current at the transmitting station, a rotating commutator at the same station, sliding brushes bearing against said commutator, means for connecting alternately by pairs, bars of the commutator with the positive and negative terminals of the current source, said means being responsive to pulsations capable of influencing the receiving apparatus, and means for connecting alternately by pairs, other bars of the commutator with points of the current source of lower potential than said ends, the latter means being responsive to pulsation not capable of influencing the receiving apparatus but of discharging and recharging the lines.

5. A system of transmitting intelligence including a transmitting station connected electrically through lines with a receiving station, a receiving apparatus at the latter station, a source of continuous current at the transmitting station, a rotating commutator at the same station, sliding brushes bearing against said commutator, means connecting alternately by pairs, bars of said commutator with the positive and the negative terminals of the current source for transmitting through the lines pulsations capable of influencing the receiving apparatus, and means connecting alternately by pairs, other bars of said commutator with points of the current source of lower potential than the said terminals for transmitting through the lines between said pulsations other pulsations not capable of influencing the receiving apparatus but of discharging and recharging the lines.

6. A system of transmitting intelligence including a transmitting station connected electrically through lines with a receiving station, a receiving apparatus at the latter station, a source of continuous current at the transmitting station, a rotating commutator at the same station, sliding brushed bearings against said commutator, means for transmitting through certain bars of the commutator and negative pulsations of high voltage, and means for transmitting through

other bars of said commutator pulsations of low voltage.

In testimony that we claim the foregoing as our invention, we have signed our names ¹⁵ in presence of two subscribing witnesses.
